METATARSAL ARCH SUPPORT

Joseph C. Howell, Fort Lee, N. J.

Application February 21, 1935, Serial No. 7,511

8 Claims. (Cl. 36—71)

This invention relates to arch supports and has particular reference to an adjustable support for the metatarsal arch.

The invention further comprehends an arch support of the indicated character which is adjustable longitudinally in the region of the metatarsal arch, which is angularly adjustable about a point located under or adjacent the metatarsal arch and which is adjustable in elevation above the sole of the shoe.

The invention more specifically comprehends, in an arch support of the type specified, an oval shaped resilient pad having a convex upper surface with the highest point substantially at the center thereof, a base to which the pad is secured, means anchored to the sole of the shoe and means of connection between the said base and anchoring means for adjusting the base vertically and horizontally with reference to the sole of the shoe.

More particularly the invention includes an improved device for adjustably anchoring the arch support to the sole of the shoe embodying a stud having means at its upper end between which the base of the arch support is clamped after the same has been set in longitudinally and angularly adjusted position.

The invention further provides a resilient arch pad and supporting and attaching means therefor, which permits of the downward flexing of the edge portions of the pad while affording a firm support for the central portion thereof to vary the degree of curvature of the upper surface of the arch so as to afford the desired support.

The invention also embodies an arch supporting accessory for any style or type of men's women's or children's shoes, which is simple in construction, which is capable of economic production and which is effective for its intended purpose.

With these and other objects in view, reference is now made to the following specification and accompanying drawings in which there has been illustrated several embodiments of the invention, while the appended claims cover variations and modifications thereof which fall within the scope of the invention.

In the drawings:

Fig. 1 is a bottom plan view of the improved metatarsal arch support.

Fig. 2 is a longitudinal sectional view therethrough, illustrating the same in applied anchored position to the shoe sole.

Fig. 3 is a transverse sectional view taken approximately on the line 3—3 of Fig. 2.

Fig. 4 is a collective perspective view of the

anchoring device for the arch supporting member showing the parts in separated juxtaposition.

Fig. 5 is a bottom plan view of a modified form of arch supporting member with parts broken away to disclose the underlying structure. 5

Fig. 6 is a longitudinal sectional view through the arch supporting member illustrating the same in applied anchored position to the shoe sole.

Fig. 7 is a transverse sectional view therethrough taken approximately on the line 7—7 of Fig. 6. 10

Fig. 8 is a collective perspective view of the means for detachably and adjustably connecting the arch support with the shoe sole, the parts thereof being shown in separated juxtaposition. 15

Fig. 9 is a bottom plan view of a metatarsal arch supporting member constructed in accordance with another form of the invention and illustrating supplemental supporting elements applied thereto. 20

Fig. 10 is a bottom plan view of the main arch supporting member. 20

Fig. 11 is a longitudinal sectional view therethrough illustrating the same in applied anchored position to the shoe sole. 25

Fig. 12 is a transverse sectional view taken approximately on the line 12—12 of Fig. 9. 30

Fig. 13 is a top plan view of a supplemental supporting element for the fourth metatarsal.

Fig. 14 is a top plan view of a supplemental supporting element for the fifth metatarsal. 35

Fig. 15 is a top plan view of a supplemental supporting element for the second metatarsal.

Referring to the drawings by characters or reference, A designates generally the arch supporting member which includes a base 10 shaped to the contour desired, in the present instance the same being of generally oval formation conforming generally to the region of the metatarsal arch. The base 10 may be constructed of leather, rubber or any analogous flexible resilient material which is normally substantially flat and is adapted to rest upon the upper surface of the sole portion of the shoe. The member A also includes a pad element 11 which is preferably of lesser area than the base 10 and has its marginal edge spaced from the marginal edge of the base and which pad is formed with a flat lower surface 12 and a convex upper surface 13, the pad being thicker at the central portion and declining towards its marginal edge where it merges into the upper surface of the base 10. The pad element 11 may be constructed of rubber, felt or any equivalent yieldable elastic cushioning material 40

45

50

55

suitable for this purpose which gives the desired support and cushioning effect.

The upper surface of the base 10, adjacent its marginal edge, is skived as at 14 so that the upper surface converges towards the lower surface and tapers off to a thin edge. The base 10 is formed with a longitudinally extending slot 15 having longitudinally spaced laterally extending notches 16 and 17 in its opposite side edges which are disposed in transverse alignment. The undersurface 12 of the pad element 11 is adhesively or otherwise secured to the upper surface of the base 10 throughout its area except for a medial portion indicated by the broken line 18 in Fig. 1 15 of the drawings, and which unsecured portion is located over and adjacent the slot 15.

In order to provide means for detachably connecting the arch support A to the sole B of the shoe, an anchoring device is employed which is 20 designated generally by the reference character C. The anchoring device includes a stud having a threaded shank 19 which depends from a relatively thin head 20 which is positioned between the upper surface of the base 10 and the unsecured medial portion 18 of the pad element 11 and which is introduced thereto by flexing or bowing the base 10 laterally and downwardly. The head 20 is provided with one or more depending key pins 21 which are disposed parallel 25 to the shank 19 and which key pins and shank extend through the slot and protrude downwardly from the base 10. Obviously under this arrangement the shank 19 may be adjusted longitudinally with reference to the arch 30 support A while at the same time the arch support may be turned with reference to the shank 19 to obtain various angular adjustments. After the shank and arch support A have been set in the relative position desired, a rigid washer 22 35 preferably of metal is applied against the underside of the base 10, the washer being provided with a central opening 23 for receiving the threaded shank 19 and eccentric openings 24 to receive the key pins 21. A lock nut 25 is threadedly engaged on the shank 19 and tightened 40 against the washer to clamp the base adjacent the slotted portion between the head 20 and the washer.

The anchoring device further includes an interiorly threaded sleeve 26 which is designed to receive the threaded shank 19 and which is rotatably mounted in an opening 27 formed in the shoe sole B, the sleeve being provided with a kerfed head 28 which is exposed at the bottom of the shoe for turning the sleeve to draw the shank 19 and the arch support downward against the upper surface of the sole, the key pins 21 being engaged in preformed key sockets 29 opening through the upper surface of the sole.

In use the lock nut 25 is loosened and the shank 19 is threadedly engaged with the rotary sleeve 26 and drawn down loosely against the upper surface of the shoe sole. The user, after trying and shifting the arch support A to various 65 positions, determines the position which properly and comfortably supports the arch. The arch, together with the stud, is disengaged and removed from the shoe and the lock nut is then tightened to retain the arch support and stud in 70 their adjusted relation. The shank 19 is then reengaged with the rotary threaded sleeve 26 and is drawn into place where it is held in place by the clamping action of the sleeve. It is, of course, obvious that pads may be used which 75 vary in thickness and the height of a pad may

be varied by inserting one or more additional washers or similar elements 22 before the stud is engaged with the sleeve 26.

In the form of the invention illustrated in Figs. 5, 6, 7 and 8, D designates generally the arch supporting member which includes a base plate 34 preferably of thin sheet metal or an equivalent flexible resilient material which is normally substantially flat and is contoured to conform substantially to the region of the metatarsal arch of the foot. In order to render the plate 34 more flexible adjacent its margin, the same is provided with radial slits 35 extending inwardly from adjacent its marginal edge. The plate is formed substantially centrally thereof with a longitudinally extending slot 36 and has outwardly extending notches 37 opening into the slot and spaced about the edges thereof, the notches on the opposite longitudinal edges being staggered with reference to each other.

A cover plate 38 of sheet metal or an equivalent flexible resilient material is spot welded or otherwise secured to the upper surface of the base plate 34 at laterally spaced points 39 lying on opposite sides of the slot 36 and substantially intermediate the length of the base plate. The cover plate 38 is of a size to completely cover the slot 36 and the notches 37 and to extend slightly there beyond.

The arch member D also includes a pad element 40 which is shaped to conform generally to the shape and size of the base plate 34 and the pad is formed with a substantially flat undersurface and a convex upper surface 41, the pad being thicker at the central portion and declining into a thin edge. The pad element 40 is superimposed upon the base plate 34 and cover plate 38 and may be adhesively or otherwise secured thereto. The pad element 40 may be constructed of rubber, felt or any equivalent yieldable elastic cushioning material which is suitable for the purpose and which provides the proper support and cushioning effect. The arch member D is completed by a thin sheath 42 of leather or an equivalent material which completely covers the upper surface of the pad element 40 and extends beyond the marginal edge thereof and which has a lower ply 43 underlying the base plate 34 and provided with a longitudinal slot 44 which exposes the slot 36 and notches 37 of the base plate. The marginal edges of the sheath are skived to a thin edge 45.

Means is provided for detachably and adjustably connecting the arch support with the sole E of the shoe and said means includes a tubular interiorly threaded stud 46 which is provided with an enlarged head 47 at its upper end, exterior threads 48 immediately below the head and longitudinal external splines 49 extending downwardly from the threaded portion 48 of the stud 50 to the lower end thereof. The head 47 of the stud is located between the upper surface of the base plate 34 and the undersurface of the cover plate 38 with the stud 46 extending downwardly through the slot 36 in the base plate. A disk like lock nut 50 is threadedly engaged over the threaded portion 48 of the stud 46 and is designed to cooperate with the head 47 to clamp the base plate in adjusted set position with reference to the stud 46, it being obvious that the arch member D may be set at longitudinally or angularly adjusted relations to the stud after which the lock nut serves to retain the adjustment. The detachable and adjustable means of connection between the arch member D and the shoe sole E

further include an anchoring device which consists of a tubular bushing 51 having a flange 52 at its upper end and formed with internal longitudinally extending splines 53 with which the 5 external splines 49 of the stud are adapted to engage to permit of the setting of the stud therein at various angular positions and to prevent rotation of the stud with reference to the bushing. It will be understood that the bushing is 10 inserted in an opening formed in the sole E with the flange 52 countersunk in the upper surface of the sole. The stud is retained in place and adjusted vertically in the bushing by means of a screw 54 which cooperates with the internal 15 threads of the stud. The screw 54 is formed at its lower end with a flange 55 which is located between the lower end of the bushing and a bottom plate 56 countersunk in the lower surface of the sole E. The screw is provided with 20 a kerfed head 57 which is exposed by a central opening 61 in the bottom plate 56 whereby the screw is swivelly mounted and is adapted to be turned from the outside of the shoe by an implement engaged with the kerfed head 57. The 25 screw, in addition to serving as a means for securing the stud and arch member D in place, is utilized for adjusting the elevation of the arch member. In order to lock the screw in its adjusted position, a set screw 58 extends through 30 an opening 62 in the bottom plate 56 and is adapted for selective threaded engagement in threaded openings 59 formed in the flange 55. The bushing and bottom plate are secured together by rivets 60 which pass therethrough and 35 through the sole E of the shoe.

In use, the lock nut 50 is loosened and the stud 40 46 is engaged in the bushing and drawn down by the screw 54. The arch member D is then shifted longitudinally or laterally into any one 45 of the notches 37 and/or turned to obtain the desired adjustment after which the screw 54 is loosened, the stud 46 removed and the lock nut 50 tightened to hold the pad and stud in relatively adjusted position. The stud is then reinserted in the bushing 51 and the screw 54 employed to draw the stud and arch member D 50 downwardly to the desired elevated position and finally the set screw 58 is utilized to secure the screw 54 against accidental turning. Under this construction and arrangement, it will be appreciated that a practically universal adjustment of the arch support is obtained.

In the form of the invention shown in Figs. 55 9 to 15 inclusive, F designates generally the arch supporting member which includes a base 65 of the desired contour, which is of generally oval formation conforming substantially to the region of the metatarsal arch. The base 65 may be 60 constructed of leather, rubber or any analogous flexible material which is normally substantially flat and is adapted to rest upon the upper surface of the sole portion G of the shoe. The member F also includes a pad element 66 which 65 conforms generally to the shape of the base 65 and is formed with a flat lower surface and a convex upper surface 67, the pad being thicker at the central portion and declining towards its marginal edge where it merges into the upper surface of the base 65, the pad element 66 being 70 constructed of rubber, felt or any equivalent yieldable elastic cushioning material suitable for this purpose. The base 65 is formed with a longitudinally extending slot 68 extending from substantially the central portion to a point adjacent the rear portion thereof, said slot having

longitudinally spaced laterally extending notches 69 along its opposite side edges which are disposed in transverse alignment. The undersurface of the pad element 66 is adhesively or otherwise secured to the upper surface of the base 75 5 throughout its area, except for a medial portion indicated by the broken line 70 and which unsecured portion is located over the slot 68 and notches 69.

Means is provided for detachably connecting the arch supporting member F to the shoe sole G which consists of an anchoring device including a threaded stud 71 having a thin disk like head 72 at its upper end which is positioned between the upper surface of the base 65 and the unsecured portion 10 70 of the pad element 66. The head 72 is provided with one or more downwardly extending key pins 73 which are disposed parallel to the stud 71 and which key pins, together with the stud, extend through the slot and protrude downwardly from the base 65. This construction and arrangement permits of the longitudinal adjustment of 15 the arch member F with reference to the stud and the turning of the arch member with reference thereto to obtain the various longitudinal and angular adjustments desired.

In this form of the invention supplemental supporting elements, designated generally by the reference character H, are adapted to be used which include a relatively thin base 74 having a longitudinal extending slot 75 and communicating notches 76 corresponding to the slot 68 and notches 69 of the base 65 of the main arch supporting member F. Each of the supplemental supports is provided with a generally forwardly directed reduced extension 77 having on the upper surface thereof, an auxiliary pad 78 of a yieldable resilient material. Each of the supplemental supporting elements H is adapted to underlie the main arch supporting member F and the extensions 77 thereof are variously shaped so that they may be optionally used to underlie and elevate various areas of the forward portion of the main arch supporting member where additional elevation and support is desired in various regions of the metatarsal arch. As shown in Fig. 9, the supplemental elements H are located under the first and third metatarsals, while in Figs. 13, 14 and 15 the elements H for the fifth, fourth and 30 35 second metatarsal are respectively shown.

After the stud 71 and arch supporting element F have been set in relative position and the desired supplemental supporting element or elements H have been applied, a washer 79 is engaged over the stud 71 and key pins 73 and a lock nut 80 are employed to bind the parts in set position. The stud is then inserted in an opening 81 which extends through the shoe sole G, while the key pins are engaged in key sockets 82. An interiorly threaded sleeve 83 is rotatably mounted in an opening 84 in the shoe sole and is adapted to receive the threaded stud 71 which is drawn downwardly together with the arch supporting member F and supplemental supporting element or 40 45 50 55 elements H. The threaded sleeve is provided with a kerfed head 85 which is exposed from the bottom of the shoe sole to afford means for turning the sleeve.

In each of the forms disclosed, when the arch supporting element is elevated adjacent the stud portion, the marginal edges of said support are flexed downwardly by the engagement of the foot therewith, while the region adjacent the stud is firmly supported in the elevated position.

What is claimed is:

1. A metatarsal arch support for shoes including a flexible resilient pad having a convex upper surface, a slotted base to which the pad is secured, means to be anchored to the sole of the shoe, means of connection between the said anchoring means and the base extending through the slot therein for adjusting the base with reference to the sole of the shoe, and means for locking the base in adjusted relation on said means of connection.
2. A metatarsal arch support for shoes including a flexible resilient pad having a convex upper surface, a slotted base to which the pad is secured, anchoring means to be extended through the sole of the shoe, and means of connection between the said anchoring means and the base extending through the slot in the base and overlying the base adjacent the said slot for adjusting the base longitudinally and angularly with reference to the sole of the shoe, said anchoring means including a screw rotatable from the exterior of the shoe for drawing the base against the inner surface of the sole of the shoe.
3. A metatarsal arch support for shoes including a flexible resilient pad having a convex upper surface, a slotted base to which the pad is secured, anchoring means to be extended through the sole of the shoe, and means of connection between the said anchoring means and the base extending through the slot in the base and overlying the base adjacent the said slot for adjusting the base longitudinally and angularly with reference to the sole of the shoe, said anchoring means including a screw rotatable from the exterior of the shoe for drawing the base against the inner surface of the sole of the shoe, and said means of connection having depending keys extending through the slot in the said base with their ends anchored in the sole of the shoe for keying the base against rotary movement with respect to the sole of the shoe.
4. A metatarsal arch support for shoes including an arch supporting member having a convex upper surface and provided with a substantially T-shaped longitudinally extending recess adjacent to and opening through its lower surface, a stud having a head and a depending threaded shank slidably adjustable in the recess, means for locking the stud and supporting member in adjusted relation, and an anchoring device to be placed in the shoe sole and engageable with the stud for detachably securing the arch supporting member in the shoe.
5. A metatarsal arch support for shoes includ-

ing an arch supporting member having a convex upper surface and provided with a substantially T-shaped longitudinally extending recess adjacent to and opening through its lower surface, a headed stud engageable with the recess to permit of slidable and rotatable adjustment of the arch supporting member with reference to the stud, and a fixed anchoring device to be placed in the shoe sole and engageable with the stud for detachably securing the arch supporting member in the shoe, and for adjusting the height of the arch supporting member with reference to the sole of the shoe.

6. A metatarsal arch support including a main arch supporting member having a normally convex upper surface and a supplemental arch supporting element adapted to underlie, elevate and support a portion of the area of the main supporting member, and a common means for anchoring the main arch supporting member to the sole of the shoe and for adjustably connecting said supplemental element with the main arch supporting member.

7. A metatarsal arch support for shoes including an arch supporting member having a convex upper surface and provided with a substantially T-shaped longitudinally extending recess adjacent to and opening through its lower surface, a headed stud engageable with the recess to permit of slidable and rotatable adjustment of the arch supporting member with reference to the stud, a fixed anchoring device to be placed in the shoe sole, engageable with the stud for detachably securing the arch supporting member in the shoe, and a supplemental arch supporting element having a slotted base adapted to underlie the main arch supporting member and to receive therethrough the stud, said element having an extension with a padded upper surface.

8. A metatarsal arch support for shoes including a flexible resilient pad having a convex upper surface, a base to which the pad is secured, said base having a longitudinally extending slot and longitudinally spaced laterally extending notches opening into the said longitudinal slot, means to be anchored to the sole of the shoe, and means of connection between the anchoring means and the base extending through said longitudinal slot in the base and adapted to be positioned in the said notches for adjusting the base longitudinally and laterally with reference to the sole of the shoe.

JOSEPH C. HOWELL.
